United States Patent Office

Des. 184,723
Patented Mar. 31, 1959

184,723

MOTION PICTURE CAMERA OR SIMILAR ARTICLE

Michael H. Froelich, Mount Vernon, N.Y., assignor to
Photique, Inc., New York, N.Y., a corporation of New
York

Application December 8, 1958, Serial No. 53,689

Term of patent 14 years

(Cl. D61—1)

Figure 1 is a front perspective view of a motion picture camera or similar article, showing my new design;
Figure 2 is a rear perspective view; and
Figure 3 is a bottom plan view thereof.

The broken line showing of legible matter in the drawing is for illustrative purposes only.

I claim:

The ornamental design for a motion picture camera or similar article, as shown and described.
